COMMUTATOR

Filed May 19, 1920

INVENTOR
JACK D. GREEN

By R. S. Berry,
Atty.

UNITED STATES PATENT OFFICE.

JACK D. GREEN, OF LA MANDA PARK, CALIFORNIA.

COMMUTATOR.

Application filed May 19, 1920. Serial No. 382,465.

To all whom it may concern:

Be it known that I, JACK D. GREEN, a citizen of the United States, residing at La Manda Park, in the county of Los Angeles 5 and State of California, have invented new and useful Improvements in Commutators, of which the following is a specification.

This invention relates to a device for timing and controlling the spark in the ignition 10 system of internal combustion engines, and an object of the invention is to provide a means for opening and closing an electric circuit at regular intervals and directing the current successively to each of a series of 15 conductors leading to sparking devices.

Another object is to provide a device of the above character embodying a series of rolling contact members and a single wiper contact member mounted to be moved successively in and out of electrical engagement 20 with the roller contact members; and in which the parts are so constructed and arranged as to be subjected to little wear and not liable to easily get out of order and 25 which will permit ready removal and replacement of the parts.

A further object is to provide a commutator which is simple, durable, efficient, and adapted to be produced at small cost.

30 Other objects will appear hereinafter.

The invention is illustrated in the accompanying drawings, in which:

Figure 1 is a view in elevation of the commutator as seen on its inner side.

35 Figure 2 is a view in vertical section as seen on the line 2—2 of Figure 1.

Figure 3 is a detail in section as seen on the line 3—3 of Figure 1.

More specifically, 4 indicates the commutator casing or shell of any suitable construction and adapted to be adjustably mounted on the wall of an engine (not shown) to extend over the end of a timing shaft 5 as is common in internal combustion 40 engine construction; the shell 4 embodying an annular rim flange 6 arranged to encircle the shaft in spaced relation to and concentric therewith.

Extending through the flange and spaced 50 at suitable intervals apart are a series of conductor stems 7 which are threaded on their outer ends to form binding posts to which the terminals of electrical conductors may be attached in the usual manner.

55 Mounted on the inner ends of each stem 7 is a turnable or rotary contact member 8

adapted to be engaged by a wiper contact member 9 mounted on a sleeve 10 carried by the timing shaft 5.

The shell is formed with an end wall 11 60 from the margin of which the flange 6 projects providing a chamber in which the wiper contact member is adapted to travel when the commutator is assembled and in operation; the wiper contact member being 65 arranged to traverse a path of travel adjacent to the inner face of the end wall. A series of recesses 12 are formed on the inner face of the end wall in which the roller contact members 8 are disposed; the stems 7 extending across the recesses and forming 70 bearings for the rollers. A sleeve or bushing 14 is interposed between the stem and roller to provide a wearing surface. For the purpose of mounting the stems 7 they are 75 preferably provided with threaded inner end portions 15 which are screwed into the end walls of the recesses, as particularly shown in Figure 2, and nuts 16 are screwed on the outer end of the stems to bear against 80 the shell and serve to lock the stems against rotation. The terminals of electrical conductors (not shown) may be connected to the stems 7 in any desired manner, as any sort of fastening may be employed, such as 85 is commonly used in devices of this character.

The roller contact members 8 are of such diameter as to project a short distance beyond the inner face of the wall 11 to extend in the path of travel of the wiper contact member 9, and as a means for permitting the wiper contact member to readily ride in and out of engagement with the roller contact members it is formed with 95 inclined flanges 17 on its opposite edges which curve outwardly relative to the rollers.

The wiper contact member is here shown as formed on an annulus 18 which encircles 100 the sleeve 10 and is secured to a flange 19 on the latter by rivets 20 or other suitable fastenings; the wiper being preferably formed of resilient or spring material to permit the necessary flexure thereof in riding over the rollers, and also cause the wiper to bear tightly against the rollers to insure 105 electrical connection therewith.

The operation of the invention is apparent from the foregoing, it being seen that 110 on rotating the shaft 5 carrying the wiper contact member, the latter will be caused to

successively wipe the rolling contact members and to pass thereover in rolling contact therewith to complete electrical connection between the shaft 5 and each of the stems 5 or binding posts.

In carrying out the invention the shell 4 is preferably formed throughout of an insulating material, so as to obviate the use of separate insulators, thus permitting the 10 commutator being formed of few parts which may be readily assembled and easily removed and replaced.

While I have shown and described a specific embodiment of my invention, I do not 15 limit myself to the exact details of construction shown, but may resort to such changes and modifications as occasion may require and as may come within the scope of the appended claim.

I claim:

20 In a commutator, a shell having an end wall formed with a marginal flange, a series of fixed stems extending thru the flange radially of the shell each of said stems being fastened against turning and projecting 25 beyond the outer periphery of the flange to form binding posts; a bushing encircling each stem interiorly of the shell, a roller contact member, mounted on each of said bushings, a shaft over the end of which the shell is mounted and a spring wiper 30 contact member carried on said shaft adapted on rotation of the shaft to be moved successively into contact with the roller contact members and to ride over the rollers 35 in rolling contact therewith under tension.

JACK D. GREEN
